CLAIM

The ornamental design for a sewing machine, as shown and described.

DESCRIPTION

FIG. 1 is a front elevational view of a sewing machine, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a reduced perspective view thereof;

FIG. 8 is a reduced perspective view of a second embodiment of FIG. 1, the only difference being the addition of a widened auxiliary bed.

FIG_1**FIG_3****FIG_4**FIG. 2

FIG. 5

FIG. 6
